(57) CLAIM

The ornamental design for a fishing rod holder, as shown and described.

DESCRIPTION

FIG. 1 is a side elevation view showing my new design as installed into the ground, and a fragmentary portion of a fishing rod in dashed lines, the fishing rod being shown for illustrative environmental purposes and forms no part of the claimed invention

FIG. 2 is a perspective view showing my new design.

FIG. 3 is a top plan view thereof.

FIG. 4 side elevation view thereof, the opposite side elevation view being a mirror image thereof.

FIG. 5 is a bottom plan view thereof.

FIG. 6 a rear elevation view thereof; and,

FIG. 7 is a front elevation view thereof.
